UNITED STATES PATENT OFFICE

AUGUST D. MEISELBACH, OF CHICAGO, ILLINOIS, ASSIGNOR OF ONE-HALF TO WILLIAM J. SANDBERG, OF CHICAGO, ILLINOIS

STRIP-CORRUGATING MACHINE

Application filed November 1, 1928. Serial No. 316,397.

This invention relates to novel means for producing a corrugated thin metal strip, and has special reference to improved means and methods for producing strips accurately corrugated in relatively square zigzag form for use particularly in producing what are known as punch or sales boards of the kind forming the subject-matter of my United States Letters Patent No. 1,713,293, granted May 14, 1929.

In the production of such boards thin sheet-metal strips equal in width to the thickness of the board are bent into zigzag form and a plurality of these strips are arranged together to form the board with a large number of relatively small cells or pockets extending through the thickness of the board. It is desirable that the corrugations have rather sharp square bends, and it is the formation of such bends in a zigzag strip with which this application has particularly to do.

In forming the thin metal strips from a flat condition to the finished zigzag corrugated form several steps are necessary, as it has so far appeared to be a physical impossibility to form the square-bend corrugations in one operation with sufficient rapidity to bring the cost within the allowed limits.

In my novel method I first partly form the corrugations, that is, I first form them with rounded tops and bottoms, and then in a further operation I finish the corrugations, making the tops and bottoms flat and the bends square. For this last step the only feasible manner is to press the partly formed strips between two interfitting dies formed to receive the partly formed strip between them and when pressed tightly together form the tops and bottoms of the corrugations flat and the bends square.

As these strips have considerable length, sometimes having as many as one hundred corrugations, and as in order to properly form the corrugations these interfitting dies must fit accurately with only clearance enough between them to receive the metal of the strip, it will be seen that the partly formed strip must accurately agree with the dies as to pitch of corrugations, that is, the distance

from center to center of the corrugations must be so exactly like the distance from center to center of the forming projections on the dies that even when a strip with one hundred or more corrugations is placed upon the dies it will lie flat on the lower die and will receive the projections of the upper die without any undue pressing of the metal at the sides of the projections.

This invention has to do particularly with means for producing the partly formed strip with such accuracy of pitch that the strip will be properly received in the forming dies for the last operation.

The invention will be more readily understood by reference to the accompanying drawings forming part of this specification and in which:

Fig. 1 is a top plan view of a strip corrugating machine made in accordance with my invention;

Fig. 2 is a vertical, longitudinal section on the line 2—2 of Fig. 1;

Fig. 3 is a fragmentary, vertical, longitudinal section on the line 3—3 of Fig. 1;

Figs. 4 and 5 are fragmentary, vertical, transverse sections on the lines 4—4 and 5—5 respectively of Fig. 1;

Fig. 6 is an enlarged, fragmentary, longitudinal section through the forming elements similar to Fig. 2 and showing a strip in process of being formed;

Fig. 7 is a section similar to Fig. 6 but without the strip;

Fig. 8 is a fragmentary, longitudinal section of a pair of die elements such as are used for the final operation of forming the square corrugations;

Fig. 9 is an enlarged, fragmentary, longitudinal section of the die members showing the partly formed strip in place on the lower die ready to receive the upper die for the final forming operation;

Fig. 10 is a view similar to Fig. 9, except that the die members have been closed together with the strip between them;

Fig. 11 is a fragmentary plan view of a sales board such as the corrugated strips are used in producing;

Fig. 12 is a perspective view of a strip

after it has passed through the machine; and Fig. 13 is a similar view of the strip in finished condition.

The machine shown in Fig. 1 consists of a base 1, provided with a longitudinal guide-way 2 in which an elongated longitudinally movable member or bar 3 is arranged and which moves freely back and forth on the base.

At one side of the top of the bar 3 is fixed a toothed rack 4. A gear wheel 5 is arranged above the rack 4 fixed on a transverse shaft 6 which is supported in fixed bearings 7 secured to the base 1 at each side of the bar 3. A crank 8 is secured to one outer end of the shaft 6 by which the shaft 6 can be manually rotated to rotate the gear 5 which in turn moves the bar 3 along the base through the guide groove 2.

At the other side of the bar 3 is provided and fixed a second toothed rack 9 which also extends the length of the bar 3. This rack as best shown in Figs. 6 and 7 has teeth 10 formed to cooperate with similar teeth 11 on a pinion 12 to form a thin sheet metal strip 13 into corrugated form with corrugations 14 having rounded tops 15 and similar rounded bottoms 16 when the strips are passed between the rack and the pinion, as illustrated in Figs. 2 and 6.

As will be seen from an examination of Fig. 7, the teeth of the rack 9 and pinion 12 are formed to provide a space 17 between them of a thickness to receive the strip 13. The strips 13 are cut of the width desired and may be formed in any length, though preferably the strips are formed of the length desired for use in making up the sales boards.

The accuracy of the pitch of the corrugations 14 is attained by leaving the pinion 12 loose on the shaft 6 and feeding the rack 9 through in under the pinion 12 by means of the rack 4 and gear 5. In other words, the pinion 12 during the corrugation forming operation merely follows the rack 9 and no pressure is applied to the strip 13 except merely the corrugation forming pressure. After the strip has thus been partly formed it is laid upon a toothed lower die member 18, as shown in Fig. 9, and a similar upper die member 19 is forced down upon same, as shown in Fig. 10, forming the rounded ended corrugations 14 into square corrugations, as shown at 20, Fig. 10. That is, the rounded tops and bottoms are flattened and the sides of the corrugations are straightened up, making the square corrugations 20 which are the ultimate object of the invention.

For the purpose of guiding the strip 13 through the machine during the corrugating operation guide plates 21 and 22 are provided. Plate 21 is fixed on one side of the machine close to the outer side of the rack 9 and the plate 22 is arranged on the opposite side 65 of the rack. The plate 22 is carried on a

horizontal guide pin 23 which is movable transversely of the machine through a fixed bearing 24. At opposite sides of the guide pin 23 the plate 22 carries horizontally projection pins 25 for supporting compression springs 26 arranged between the bearing member 24 and the plate 22. These springs tend to hold the plate 22 yieldingly against the adjacent edge of a strip 13 as it passes through between the plates 21 and 22 and is being fed between the rack 9 and the pinion 12. These guide plates hold the strip transversely and cause it to be fed straight through the machine.

In Fig. 11 I have shown a corner of one of the sales boards 27 made up of a plurality of the corrugated strips 13 laid together so that the square corrugations make square cells or openings 28 in the board. These strips are clamped together between end clamping strips 29 by clamping bolts 30. It is desired that the corrugations be as square-cornered as possible so that the strips will properly pack together when clamped together to form a board, and also so that the pitch of the openings in the board will be uniform for the purpose both of further processes through which the board is put in completing it and for use with filling machines for placing the sales indications in the cells 28.

As many modifications of my invention will readily suggest themselves to one skilled in the art, I do not limit or confine my invention to the specific details of construction herein shown and described.

I claim:

1. In a machine for transversely corrugating sheet-metal strips, an elongated longitudinal movable member, a longitudinally arranged toothed rack carried by the member, a toothed pinion above the rack intermeshing therewith and mounted on a shaft for free rotation, the rack and pinion adapted to receive the strip to be corrugated between them and to be corrugated as the rack passes past the pinion, a second toothed wheel arranged above the movable member and of larger diameter than the pinion, a second rack fixed on the member parallel with the first rack and with which second rack said second toothed wheel meshes, the second toothed wheel rigidly mounted on said shaft for rotation therewith, and means for rotating said shaft.

2. In a machine for corrugating strips of sheet metal, a shaft mounted in bearings for rotation, a toothed wheel carried by the shaft and freely rotatable thereon, a second toothed wheel carried by the shaft and fixed thereon, a member movable transversely in relation to the shaft, two toothed racks fixed on said member, one thereof meshing with each of said toothed wheels, and means for rotating said shaft, the strip to be corrugated being

passed between the toothed wheel, which is freely rotatable on the shaft, and its co-operating rack, the other rack and toothed wheel being operative to move said member in relation to the shaft.

5 3. In a machine for corrugating strips of sheet metal, two co-operating, intermeshing, toothed members between which the strips are passed to be corrugated, means for positively moving one of said members, the other member being free to follow the positively moved member.

10 4. In a machine for corrugating sheet-metal strips, a toothed rotatable member and a co-operating, intermeshing, toothed, longitudinally movable member, means for positively moving one of said members, the other member being free to follow the positively moved member.

15 5. In a machine for corrugating sheet-metal strips, a rotatable toothed member and a co-operating, intermeshing toothed rack, the strips being adapted to be passed between the co-operating teeth to be corrugated, means for positively moving the rack, the rotatable toothed member being free to follow the movements of the rack.

20 In testimony whereof, I have hereunto set my hand, this 17th day of October, 1928.

25 30 AUGUST D. MEISELBACH.
